(57) **CLAIM**

The ornamental design for a mesh tray, as shown and described.

DESCRIPTION

FIG. 1 is a front perspective view of a first variant of a mesh tray;

FIG. 2 is a front view of the mesh tray of FIG. 1;

FIG. 3 is a side elevation view of one side of the mesh tray of FIG. 1;

FIG. 4 is a side view of the mesh tray of FIG. 1;

FIG. 5 is a top perspective view of the mesh tray of FIG. 1;

FIG. 6 is an enlarged detail view of area 6 circumscribed within the mesh tray of FIG. 5;

FIG. 7 is a bottom perspective view of the mesh tray of FIG. 1;

FIG. 8 is a perspective view of the mesh tray of FIG. 1 in a use configuration with environment;

FIG. 9 is a perspective view of the mesh tray of FIG. 1 in a use configuration with environment;

FIG. 10 is a front perspective view of a second embodiment of a mesh tray;

FIG. 11 is a front view of the mesh tray of FIG. 10;

FIG. 12 is a side elevation view of one side of the mesh tray of FIG. 10;

FIG. 13 is a side view of the mesh tray of FIG. 10;

FIG. 14 is a top perspective view of the mesh tray of FIG. 10;

FIG. 15 is an enlarged detail view of area 15 circumscribed within the mesh tray of FIG. 14;

FIG. 16 is a bottom perspective view of the mesh tray of FIG. 10;

FIG. 17 is a perspective view of the mesh tray of FIG. 10 in a use configuration with environment;

FIG. 18 is a perspective view of a mesh tray of FIG. 10 in a use configuration with environment;

FIG. 19 is a front perspective view of a third embodiment of a mesh tray;

FIG. 20 is a front view of the mesh tray of FIG. 19;

(Continued)

FIG. 21 is a side elevation view of one side of the mesh tray of FIG. 19;
 FIG. 22 is a side view of the mesh tray of FIG. 19;
 FIG. 23 is a top perspective view of the mesh tray of FIG. 19;
 FIG. 24 is an enlarged detail view of area 26 circumscribed within the mesh tray of FIG. 23;
 FIG. 25 is a bottom perspective view of the mesh tray of FIG. 19;
 FIG. 26 is a perspective view of a mesh tray of FIG. 19 in a use configuration with environment; and,
 FIG. 27 is a perspective view of a mesh tray of FIG. 19 in a use configuration with environment.
 The dot-dash-dot broken lines in FIGS. 5, 6, 14, 15, 23, and 24 depict the boundaries of the enlargements that form no part of the claimed design. The evenly spaced broken lines in FIGS. 8, 17, and 26 depict environment of a propagation tray that forms no part of the claimed design. The evenly spaced broken lines in FIGS. 9, 18, and 27 depict environment of a propagation tray and cover that form no part of the claimed design.

1 Claim, 21 Drawing Sheets
